ATTORNEY

UNITED STATES PATENT OFFICE

145,958

DESIGN FOR A MERCHANTISE DISPLAY CABINET

Clyde T. Smith, New York, N. Y.

Application October 8, 1945, Serial No. 122,625

Term of patent 7 years

(Cl. D80—11)

To all whom it may concern:

Be it known that I, Clyde T. Smith, a citizen of United States, residing at New York, in the county of New York and State of New York, have invented a new, original, and ornamental Design for a Merchandise Display Cabinet, of which the following is a specification, reference being had to the accompanying drawing, forming part thereof.

In the drawing:

Fig. 1 is a perspective view of the merchandise display cabinet showing my new design;

Fig. 2 is a side view of the merchandise display cabinet showing my new design.

I claim:

The ornamental design for a merchandise display cabinet, as shown.

CLYDE T. SMITH.
